(57) **CLAIM**

The ornamental design for a light pole bracket for holding an inflatable balloon, as shown and described.

DESCRIPTION

FIG. 1 is a side view of the light pole bracket for holding a flexible rod next to a light pole, the flexible rod attached to a balloon holder cup, the balloon holder cup attached to an inflatable balloon.

FIG. 2 is an enlarged front perspective view of the light pole bracket for mounting on the light pole and attaching to the flexible rod shown in FIG. 1.

FIG. 3 is a side perspective view of the light pole bracket for the mounting on the light pole.

FIG. 4 is an opposite side perspective view of the light pole bracket for mounting on the light pole; and,

FIG. 5 is a top perspective view of the light pole bracket for mounting on the light pole.

The broken lines showing a light pole, light pole mounting straps, a flexible rod, a balloon holder cup and an inflatable balloon in FIG. 1 illustrate environmental matter and form no part of the claimed design.
